DESIGN FOR A PLAQUE

Application filed April 28, 1932. Serial No. 43,643. Term of patent 3½ years.

To all whom it may concern:

Be it known that I, PASQUALE BENEDUCE, a subject of the King of Italy, residing in Hoboken, in the county of Hudson and State of New Jersey, have invented a new, original, and ornamental Design for Plaques, of which the following is a specification, reference being had to the accompanying drawings, forming part hereof.

In the drawings, Fig. 1 is an elevation of a plaque showing my design, and

Fig. 2 is a vertical section through Fig. 1. The ornamental design herein shown has an arch-shaped recess adapted to contain a figure in relief preferably of religious character, the background for the figure being a representation of clouds in relief.

I claim:

The ornamental design for a plaque as shown and described.

PASQUALE BENEDUCE.
